his Attorney.

UNITED STATES PATENT OFFICE.

WILLIAM WEIS, OF PERHAM, MINNESOTA.

CURB-BLOCK.

1,269,888.

Specification of Letters Patent. Patented June 18, 1918.

Application filed December 1, 1916. Serial No. 134,440.

To all whom it may concern:

Be it known that I, WILLIAM WEIS, a citizen of the United States, residing at Perham, in the county of Ottertail and State 5 of Minnesota, have invented certain new and useful Improvements in Curb-Blocks, of which the following is a specification.

My invention relates to curb blocks for constructing wells and has for its object to

- 10 provide a block which is formed with a recess extending substantially throughout the length of the block for the purpose of providing a step by means of which ingress or egress from the well may be had and
- 15 which serves to make the block lighter, thereby economizing in material without greatly reducing the strength of the block. A still further object is to form the lower portion of the block so that an extended inclined surface is provided on which the whole foot may rest in a comfortable position, said lower portion extending out beyond the inner surface of the block and sloping back to form a continuous surface with the upper portion of the block immediately below it.
- 25
- 30

The full objects and advantages of my invention will appear in connection with the detailed description thereof and are particularly pointed out in the claim.

In the drawings, illustrating the application of my invention in one form,—

Figure 1 is a perspective view of my improved curb block showing the step. Fig. 35 2 is a plan view of a well with one of the blocks shown in section. Fig. 3 is a vertical sectional view of the well shown in Fig. 2.

My improved curb block is preferably 40 made of concrete and is formed in suitable molds constructed for the purpose. The blocks may be made segmental so that a number of blocks 10, of which I prefer to have four, will form a complete circular 45 course, as is clearly shown in Fig. 2. The ends 11 and 12 of each block are rectangular, as shown in Fig. 2, being somewhat higher than wide. The inner surface 13 of each block is formed with a recess 14 ex- 50 tending substantially from one end of the block to the other except for end portions 15 and 16, while the outer wall 17 and the top and bottom 118 and 119 are formed smooth. Recess 14 extends back into the 55 block about one-half of the thickness there- of and is bounded by a vertical wall 18, two

sloping end walls 19 and 20, a curved roof 21 which meets surface 18 substantially in a line and an inclined lower surface 22 of a ridge 23 which extends beyond the inner 60 surface 13 of the block proper and which has a surface 24 sloping back to meet the upper portion of the next lower block and to form a continuous surface with the surface 21 thereof.

In constructing wells a number of the blocks are piled in courses upon one another to break joints on the ground where the well is to be dug. The earth is then undermined beneath the blocks which causes the 70 same to sink and to form a lining within the shaft so dug which lining is capable of resisting the pressure of the earth tending to cave the same in and which will not deteriorate with time. The lining may be installed within a well previously constructed of wood or other material without the removal of the wood by merely commencing at the bottom and building upward.

In using the steps formed within the blocks 80 the whole foot may be placed upon the surface 22 as indicated in dotted line in Fig. 3, which surface as will be noted is inclined to permit the feet to rest in a convenient and comfortable position, which is especially desirable when water is struck and the operator cannot stand upon the ground to work but must remain supported upon the wall structure. In climbing it will be found that with only four blocks to the 90 course and with a recess of considerable circumferential extent, that a succession of steps will be provided which are substantially one below the other even though the blocks are laid to break joints, thus permitting the operator to move straight upward with the greatest ease.

The advantages of my invention are manifest. The blocks can be easily molded by a simple mold since a perfect draft is secured 100 in any portion of the same. It will be noted that the block is formed with the major mass of the material at the bottom, which permits of proper setting of the cement without danger of the wall structure breaking down during setting, and also gives the block the greatest strength.

I claim:

A curb block for wells comprising a body portion having a circumferential depression 110 formed with an inclined lower surface and a curved wall extending from the top of

the block inward to the inner part of the depression, and a ridge formed along the lower portion of said block projecting out beyond the same having a surface serving as an extension of said inclined lower surface of the body and also having an inwardly-sloping wall adapted to meet the previously-mentioned wall of another block

positioned below it to form a regular continuous surface therewith.

In testimony whereof I affix my signature in presence of two witnesses.

WILLIAM WEIS.

Witnesses:

A. S. BARRON,
A. G. HENY.
